UNITED STATES PATENT OFFICE.

CHARLES ANGUS MACINTOSH, OF SPENCERPORT, NEW YORK.

IMPLEMENT FOR REMOVING COVERS OR CLOSURES.

Application filed February 13, 1925. Serial No. 8,959.

This invention relates to implements for removing covers, lids or closures and has for its object to provide a device by the use of which various types of lids or closures can be readily removed. According to the present invention the implement comprises means at one end for cutting off hermetically sealed covers and means at the other end for prizing off removable flanged covers.

15 A device for removing corks may be arranged to be brought into or out of operative position between the cutting and prizing means mentioned in the preceding paragraph.

15 The invention and operation thereof will be hereinafter described in detail and the essential features thereof will be more particularly pointed out in the appended claim.

Referring to the accompanying drawings 20 which illustrate a convenient embodiment of the invention:—

Figure 1 is an elevation of the invention, Figure 2 is a section through the axis of Figure 1, and

25 Figure 3 is an end elevation looking on the left-hand end of Figure 2.

The device comprises a rigid metal rod 1 with one end tapered to a point and offset from the axis of the main portion of the rod 30 as at 2. Rotatably and slidably mounted on the rod is a circular cutter comprising a cutting edge 3 and flange 4. The part 3 is of piano-convex lens-shape while the part 4 is conical, the two parts being integrally joined by a short cylindrical portion.

Upon the other end of the rod 1 is mounted a handle, preferably of hollow or cupped formation, as indicated at 5. The handle, as shown, may be formed with a sleeve 6 at 40 one end by means of which the handle is secured to the rod, the sleeve closely embracing the rod and being held thereon by a rivet 7. At a suitable distance from the rounded end 8, the handle is provided with inwardly projecting lugs or claws 9 preferably formed integral with the handle. Means such as a pin 10 is provided for preventing the cutter 3—4 from sliding off the rod 1.

50 With an implement constructed as described many forms of can closure or lid may be readily removed. For opening a can which has to be opened by cutting off the cover, the pointed end 2 is thrust through the centre of the can cover. The cutter is

then moved along the rod to bring the cutting edge 3 to a position adjacent to outer edge of the can cover and the flange 4 slightly beyond the outer edge of the cover. Downward pressure on the handle 5 will now cause the rod 1 to turn about the pointed end 2 and the cutting edge 3 to cut into the cover. By holding the can with one hand and rotating the implement with the other hand in a plane parallel to that of the can cover the cutter will rotate on the rod and make a continuous cut round the edge of the cover, the cutter being automatically guided in the desired path by reason of the fact that the cutting edge 3 engages the inside of the can 70 while the flange 4 engages the outside of the can.

If a detachable can cover of the flanged type or certain types of bottle closures are to be removed the lugs 9 are inserted under the flange of the cover or lid. By raising the rod 1 the end 8 of the handle will engage the cover and by continuing the movement the cover is removed without difficulty.

For withdrawing corks from bottles a cork screw 11 may be provided. The inner end of the screw may have a flat boss 12 pivoted at 13 to the end of the rod 1 which may be forked for the purpose as shown. Means may be provided for retaining the screw 11 80 in idle position within the handle or in operative position. Such means may for example, consist of a leaf spring 14 secured to the rod 1. The free end of the spring engages a notch 15 to retain the screw yieldingly in 85 idle position. To bring the screw into operative position it is pivoted until a notch 16 is engaged by the end of the spring, a projection 17 being provided to facilitate manipulation of the screw into operative position.

It will be seen that by the use of the single implement described several different types of covers and closures may be easily and quickly removed.

The specific construction hereinbefore described may be departed from to embody any modifications which are within the scope of the appended claim.

What I claim is:

An implement for removing covers or closures comprising a rigid metal rod having an offset pointed end, a handle secured on the other end of the rod, and a circular cutter rotatably and slidably mounted on said rod,

said cutter consisting of a plano-convex portion forming a cutting edge and arranged with the plane surface nearer the pointed end of the rod, and a shallow conical flange 5 of substantially the same diameter as the plano-convex portion, said flange being integrally connected to said plano-convex por-

tion by a short cylindrical portion with the conical surface facing the convex surface, the curve of the convex surface being of small 10 radius.

In testimony whereof I affix my signature,

CHARLES ANGUS MacINTOSH.
